Inventor,

Albert D. Ray

By Obed B. Billman

Attorney.

UNITED STATES PATENT OFFICE.

ALBERT D. RAY, OF CLEVELAND, OHIO.

REVERSIBLE CUFF.

No. 902,909.

Specification of Letters Patent.

Patented Nov. 3, 1908.

Application filed May 7, 1907, Serial No. 372,408. Renewed April 20, 1908. Serial No. 428,145.

To all whom it may concern:

Be it known that I, ALBERT D. RAY, a citizen of the United States, residing at Cleveland, in the county of Cuyahoga and 5 State of Ohio, have invented certain new and useful Improvements in Reversible Cuffs, of which the following is a specification.

My invention relates to improvements in 10 reversible-cuffs attached to the sleeves of shirts and similar apparel, and the primary object of the invention is to provide a generally-improved cuff of the class known as the "attached sleeve cuff"; the cuff being 15 reversibly-attached directly to the end of the sleeve in such a manner as to permit of its reversal as desired so that either side and edge may be exposed and projected, respectively, while being worn. In this way 20 the cuff provides double service and may be worn for about twice the length of time of the ordinary "attached cuff", or "separable cuff", and, at the same time, insures an 25 equally clean exterior by reason of the fact that when one surface and edge has become soiled, the cuff may be reversed and the unsoiled surface and edge exposed.

With these ends in view, the invention 30 consists in the novel construction, arrangement, and combination of parts, hereinafter described, illustrated in the accompanying drawings, and particularly pointed out in the appended claims.

Referring to the drawings, forming a part 35 of this specification, Figure 1, is a view of one end of the improved cuff-band with attaching-plait or seam formed therewith for reversible-attachment to the end of a sleeve. Fig. 2, a detail perspective view of the 40 extended cuff-band with a portion of the attached sleeve showing manner of attachment and reversal. Fig. 3, a view showing full cuff exposed and the preferred position when first worn, the dotted lines showing 45 hinged attaching-plait, and sleeve on under side of cuff. Fig. 4, a view showing cuff reversed exposing only part of cuff, the dotted line indicating the outline of part of cuff turned under sleeve and not exposed.

50 Similar characters of reference designate

like parts throughout all the figures of the drawings.

The improved reversible-cuff is made up or formed by the usual rectangular cuff-band 1, preferably made up of two or more 55 strips or thicknesses of cloth, as shown, one of which is provided with an attaching-strip, fold, or plait 2, extending lengthwise thereof, preferably formed by means of a fold or plait formed with one of the strips of 60 cloth as shown most clearly in Figs. 1, and 2, of the drawings, said fold or plait having its sides secured together at its base by means of a seam 2a. The usual button-holes 3, are formed in the ends of the cuff-band, 65 one, two, or three in number, but, preferably the latter and arranged as shown. The attaching-plait or fold 2, is preferably arranged midway of the sides of the cuff-band, 70 as shown, and when the ends of the cuff-band are provided with button-holes in alignment with the attaching-plait or fold, the latter is provided with arched recesses or cut away portions 4, to allow for the insertion of the 75 cuff-button. The edge of the sleeve 5, is attached or sewed to the plait or fold 2, 80 preferably by means of a seam 6, except where the edge of the sleeve passes over or across the central button-hole, this point being left unfastened and forms an arch or fold over the button-hole.

It will be observed that the plait or fold 2, forms a hinged attaching-plait or fold midway of the ends of the cuff when the latter is formed by uniting the ends of the 85 cuff-band by means of the usual cuff-button, as shown in Figs. 3, and 4, and that when the cuff-band is opened or extended, as shown in Fig. 2, it may be readily reversed as desired.

From the foregoing description, taken in connection with the accompanying drawings, the operation and advantages of my invention will be readily understood.

Having thus described my invention, without having attempted to set forth all the forms in which it may be made, or all the modes of its use, I declare that what I claim and desire to secure by Letters Patent, is,—

50 A reversible-cuff, comprising a cuff-band 100

provided with a hinged attaching-plait or fold extending throughout the entire length and near the longitudinal center thereof and provided with arched recesses near its ends, 5 button-holes in alinement with said plait or fold and within said arched recesses, and a sleeve attached to said plait or fold.

In testimony whereof I have affixed my signature, in presence of two witnesses.

ALBERT D. RAY.
